CLAIM

We claim the ornamental design for a gaming machine display, as shown and described.

DESCRIPTION

FIG. 1 is a front perspective view of a gaming machine display showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom side view thereof.

The ornamental design which is claimed is shown in solid lines in the drawings. The broken lines in the drawings are for the purpose of illustrating environmental structure, which form no part of the claimed design.
